E. B. BROOKS.
WATER WHEEL.

No. 44,509.

Patented Oct. 4, 1864.

Inventor
E. B. Brooks
per. M. M. G.
Attorney

UNITED STATES PATENT OFFICE.

E. B. BROOKS, OF MICHIGAN CITY, INDIANA.

IMPROVEMENT IN WATER-WHEELS.

Specification forming part of Letters Patent No. 41,509, dated October 4, 1864.

To all whom it may concern:

Be it known that I, E. B. BROOKS, of Michigan City, in the county of La Porte and State of Indiana, have invented a new and Improved Water-Wheel; and I do hereby declare that the following is a full, clear, and exact description of the same, reference being had to the accompanying drawings, forming part of this specification, in which—

Figure 1 is a vertical central section of my invention, taken in the line *x*, *x*, Fig. 2. Fig. 2 is a plan or top view of the same.

Similar letters of reference indicate corresponding parts in the two figures.

This invention relates to a new and improved horizontal water-wheel; and it consists in the employment or use of a dome and a series of gates arranged in such a manner that the water will be properly directed to the buckets of the wheel and a large percentage of the power of the water obtained.

The invention also consists in a novel manner of connecting the dome to the annular plate of the framing of the wheel, as herein-after fully shown and described, whereby said connection is not only obtained, but also the pintles of the gate-hinges.

The invention further consists in the combination of the buckets with the gates and chutes, all arranged, as hereinafter described, to cause the water to act in a favorable manner upon or against the buckets.

To enable those skilled in the art to fully understand and construct my invention, I will proceed to describe it.

A represents the wheel, which is composed of a circular band or rim, *a*, connected by arms *b* to a hub *c*, which is firmly keyed on a vertical shaft, *B*. On the exterior of this rim *a* the buckets *d* of the wheel are secured. The buckets have their bottoms *e* of curved form, their concave surfaces being uppermost and inclined. The rims *a* form the inner sides of the buckets, and the outer sides, *a*^x, are vertical and parallel with the rim *a*. The bottoms *e* are not of equal width. They gradually widen from their upper to their lower ends. The buckets slightly lap into each other, the inner end of one bucket fitting a short distance into the mouth of the one directly behind it, as will be fully understood by referring to Fig. 1, in which the position of the buckets is indicated by the dotted lines.

C represents a framing on which a horizontal annular plate, *D*, is firmly secured. The inner edge of this plate is about on a level with the upper edge of the rim *a*, and a space, *f*, is allowed between the inner edge of the plate *D* and the rim *a*, said space being equal in width to the back and narrowest parts of the buckets. The front part therefore of the outer sides, *a*^x, of the buckets are considerably beyond the inner edge of the plate *D*, as shown in Fig. 1.

E is a dome of semi spherical form, which is placed directly over the rim *a*, the upper edge of the latter being directly under the lower edge of the former, as shown clearly in Fig. 1. This dome is held in position by a series of horizontal bolts, *g*, the outer ends of which are attached to the plate *D*, and the inner ends secured to the dome, said bolts extending across the space *f*, between the plate *D* and the dome *E*, and forming the pintles of the hinges of a series of gates, *F*. These gates are curved longitudinally, corresponding to the curvature of the lower end of the dome *E*, and they gradually increase in width from their back or hinged ends to their front ends, as shown clearly in figures. Each gate *F* is connected at its front end by a rod, *G*, with a plate, *H*, which is fitted loosely on the wheel-shaft *B* above the dome *E*. By raising and lowering this plate *H* the gates, *F* may be simultaneously opened and closed.

I represents a series of plates which are attached vertically to the annular plate *D* at the outer edges of the gates *F*. These plates *I* have their upper edges inclined corresponding to the inclination of the gates *F* when raised or opened to their fullest extent. The plates *I*, in connection with the gates *F* and the dome *E*, form chutes to direct the water properly to the buckets. The water first acts upon or against the buckets by impact, and in descending down through the buckets a reacting force is obtained, and when the water leaves the buckets all its effective power is obtained—that is to say, as great a percentage of it as it is possible to obtain. The gradually-increasing width of the buckets admits of a free discharge of the water, so that the latter cannot act as a drag to the wheel, and said water, after first striking the buckets about at right angles, reacts both downward and outward by gravity and centrifugal force, so that the water

in passing through the buckets has its momentum fully transferred to them.

Having thus described my invention, what I claim as new, and desire to secure by Letters Patent, is—

1. The dome E, in combination with the wheel A, horizontal annular plate D, gates F, and plates I, all arranged substantially as herein set forth.

2. The connecting of the dome E to the annular plate D by means of the bolts g, arranged as shown, so as to serve as pintles for the hinges of the gates F, as described.

3. The gradually-enlarged buckets d, from their inner to their outer ends, with concave inclined bottoms e, in combination with the chutes composed of the gates F, plates I, and dome E, substantially as and for the purpose specified.

E. B. BROOKS.
